INTERMITTENT VENOUS OCCLUSION
APPARATUSStanley A. Kroll, Queens Village, N. Y., assignor
to U. M. A. Inc., New York, N. Y., a corporation
of New York

Application May 1, 1937, Serial No 140,142

12 Claims. (Cl. 128—299)

My invention relates generally to an improved apparatus for increasing collateral circulation in the treatment of peripheral vascular disease, and more particularly the invention relates to an improved machine for automatically producing intermittent venous occlusion in an extremity wherein there exists deficient circulation.

One of the main objects of my present invention is to provide an automatically operating apparatus for inflating a pneumatic cuff to a predetermined air pressure; a timing mechanism controlling the period of inflation of the cuff; and the apparatus further including a single device which acts to predetermine the maximum inflation pressure of the cuff, to indicate the pressure in the cuff, and to restore the inflation pressure to said maximum pressure whenever the cuff pressure decreases during an inflation period.

Another important object of my invention is to provide an automatically operating cuff inflation apparatus of the type using a timing mechanism to regulate the cuff inflation and deflation periods, a frequency selector device for pre-setting the time durations of these periods; and a pressure-responsive means being used for simultaneously keeping the cuff inflated to a desired pressure during inflation periods and indicating the changes in pressure in the cuff during such inflation periods.

Another important object of this invention is to provide a novel and highly improved pressure-responsive control mechanism for a compressor-motor unit, wherein the motor circuit is dependent for energization upon the pre-setting of a motor circuit control element to a position corresponding to a desired pressure, and a pressure-actuated member being employed to actuate said control element to de-energize said motor circuit when the member is adjusted to the abovementioned pressure position.

Yet another object of my invention is to provide a highly flexible and reliable timing mechanism for an air compression apparatus; the mechanism being capable of energizing and de-energizing a motor circuit in alternate periods, and a frequency selector device being associated with the timing mechanism to provide a wide range of time combinations for the aforesaid alternate periods.

An object of my invention, in addition to those above, is the provision of an air compression system for treating peripheral vascular disease, wherein the system employs an air reservoir having numerous outlets to pneumatic cuffs, and auxiliary air taps being provided for actuating a

pressure control device, restoring the reservoir pressure to atmospheric after the expiration of predetermined periods of time and permitting entry of air under pressure when a motor-compressor unit is rendered operative.

And still another object of the invention may be stated to reside in the provision of an alternate venous occlusion apparatus wherein the various units are compactly assembled in a cabinet whose operating panel is provided with a pressure selector member adjustable to select and indicate any cuff inflation pressure of a range of suitable pressures; a frequency selector mechanism to select a desired one of a range of inflation cycle combinations; a plurality of visual pressure indicators adapted to indicate the condition of the compressor unit at any time; and pressure couplings for one or more pneumatic cuffs.

Still other objects may be stated to reside in the general improvement of automatic apparatus for treating peripheral vascular disease; and more especially to provide an apparatus which is not only mechanically reliable, durable and efficient in operation, but is characterized by its relative simplicity of assembly and manipulation.

The novel features which I believe to be characteristic of my invention are set forth particularly in the appended claims; the invention itself, however, as to both its organization and mode of operation will best be understood by reference to the following description taken in connection with the drawings in which I have indicated a construction whereby my invention may be carried into effect.

In the drawings:

Fig. 1 is a front view of the operating panel of a cabinet housing an apparatus embodying the invention.

Fig. 2 is a view of the apparatus when seen from the rear of the cabinet.

Fig. 3 is a section taken along line 3—3 of Fig. 2, and looking in the direction of the arrows.

Fig. 4 is a view taken along section line 4—4 of Fig. 3, looking in the direction of the arrows.

Fig. 5 is a section of an indicator detail taken on line 5—5 of Fig. 4, looking in the direction of the arrows.

Fig. 6 is a sectional detail of the timing disc.

Fig. 7 is a detailed view, partly sectioned, of the combination pressure gauge and motor control switch.

Fig. 8 is a section taken along line 8—8 of Fig. 7, looking in the direction of the arrows.

Fig. 9 is a schematic representation of the

mechanical elements and electrical circuits of the present apparatus, and

Fig. 10 is a detailed view, partly sectioned, of the quadrant gear and associated pinion in Fig. 7.

5 Referring now to the accompanying drawings, wherein like reference characters in the different figures designate similar constructional elements, there is shown in Figs. 1 and 2 a cabinet 1 upon whose base 2 is securely affixed the intermittent 10 venous occlusion apparatus chassis; the operating panel 3 is rigidly secured in position in one opening of the cabinet, while the rear opening (seen in Fig. 2) will be closed by a hinged panel. The panel 3 is preferably fabricated of an insulation 15 material such as a phenol condensation product, hard rubber or the like. As shown in Fig. 1, the operating panel 3 is provided with the manipulating knob 4 of the frequency selector switch; the adjusting knob 94 of the air pressure control mechanism; the air pressure gauge 37; the viewing lenses 7 of the pressure indicator lamps; the pneumatic cuff couplings 31; and the power control switch 9. Before explaining the 20 constructional details of the various components 25 of the apparatus, the schematic representation of Fig. 9 will be considered. The components comprise, in general, a motor 10 energized from a source of alternating current 11, the motor being mechanically coupled to an air compressor 12. 30 The numeral 11 designates a source of alternating current which is used to energize the entire system shown in Fig. 9. The motor 10 is an alternating current operated motor, and is connected in circuit with source 11 in the following manner. One terminal of the motor is connected through lead 26 and lead 27 to one side of the source 11. The other terminal of the motor is connected to the other side of source 11 through a path which includes lead 35 25, contact 24, armature 23, lead 21, lead 20, contact 19, armature 18, lead 17, fuse 16 and "on-off" switch 9. The motor 10 drives, by any suitable mechanical coupling, a centrifugal air compressor 12, the latter being mounted on a 40 45 pair of soft rubber cushions 13 to eliminate vibrations. The air compressor has an air coupling to an equalizer 14, and the latter feeds an air reservoir 15 through a check valve 30.

The reservoir 15 is provided with six outlets.

50 Three of these outlets are denoted by the numerals 31, and they are adapted for connection to pneumatic cuffs. One of these cuffs is conventionally represented by the numeral 32, and the cuff is shown connected to a special coupling connector 33. The other three outlets are represented by the numerals 34, 35 and 36. Outlet 34 feeds a combined pressure indicating and motor control gauge 37. The outlet 35 is coupled to the equalizer 14 through the check valve 30. 55 The outlet 36 is a release outlet, and its function will be described at a later point. The check valve 30 is of a well-known and conventional construction, and is provided with inlet and outlet ports. The inlet port is coupled by 60 the rubber tube 38' to the equalizer outlet, while the outlet port of the check valve is coupled by tube 35' to the port 35. The air connection between the inlet and outlet ports of the check valve is controlled by a rubber diaphragm 38, 65 which is normally biased to prevent air connection between these ports. The numeral 39 denotes a spring pressed thimble which biases the diaphragm 38. The diaphragm 38 is normally seated, unless the air pressure from the equalizer 70 75 14 exceeds a predetermined setting of the spring

of the check valve. The chief function of the check valve is to prevent reversal of air flow when the air pressure in the equalizer 14 is less than the air pressure in reservoir 15. In other words, as long as the motor 10 is operating to 5 pump air into reservoir 15, then the check valve diaphragm 38 will be in "open" position. As soon as the motor 10 ceases operation, the diaphragm 38 closes the air connection to the equalizer.

Considering, now, the pressure release valve 10 36, it will be understood that it includes a conventional needle valve construction. The needle valve is normally unseated by the spring-tensioned insulator bar 40. The spring 41 normally draws the bar 40 in a direction to unseat the 15 pressure release valve. The armature 18 is drawn towards the relay coil 42, and it is to be understood that the relay coil 42 and armature 18 are schematically represented. The armature 18 is fixedly pivoted at point 43, and when it is drawn 20 towards the coil 42 the bar 40 is lifted upwardly with the result that the pressure release valve closes. There will now be described the electrical circuit which includes the relay coil 42 that controls the pressure release valve. One terminal 25 44 of the relay coil may be traced to one side of the alternating current source 11 through a path which includes lead 45, contact finger 46, metallic timer disc 47, the specific contact finger 48, lead 49, terminal 50, the contact point 51 of the 30 rotary frequency selector switch 52, the adjustable contactor 53, terminal 54, lead 55, fuse 16, switch 9.

The opposite terminal 56 of the relay coil 42 may be traced to the source 11 through a path 35 which includes lead 57, terminal 58 of the switch section of the pressure gauge 37, lead 59, the contact arm 60, the metallic pivot post 61, lead 62, terminal 63, lead 64, lead 65 and lead 27. When the contactor 18 is drawn into contact with terminal 19, the following circuit is closed: From the metallic pivot 43 through lead 17, fuse 16 and switch 9 to one side of source 11, the terminal 19 being connected to the other side of source 11 through a path which includes lead 20, relay 45 coil 70, lead 71, terminal 72, lead 73, contact arm 74, metallic post 61, lead 62, terminal 63, lead 64, lead 65 and lead 27.

The energization of coil 70 is accomplished, as explained above, by closing the switch 18-19. 50 As soon as the coil 70 is energized, and it is to be understood that the coil 70 is part of a relay device which is other than the relay device described in connection with relay coil 42, the electrical energizing circuit for motor 10 is completed 55 in the following manner: The coil 70 draws the contact arm 23 into circuit-closing connection with terminal 24. The motor circuit may then be traced through a path which includes contactor 23, terminal 24, lead 25, through the terminals 60 of the motor 10, lead 26, lead 27, through the source 11, switch 9, fuse 16, lead 17, metallic pivot 43, contactor 18, contact 19, lead 20, lead 21 and metallic pivot 22. It will now be seen that to open the motor circuit the coil 42 must be de- 65 energized thereby permitting switch 18-19 to open, and thus, in turn, deenergizing coil 70. Opening of the circuit of motor 10 would result from the deenergization of coil 42, even though element 80 failed to open contacts 23, 24. The 70 result is that the switch 23-24 is automatically opened by virtue of the release of the element 80 which conventionally represents any well-known form of actuating mechanism for electro-magnetic relays. For example, the element 80 may 75

be gravity-operated, or can be spring tensioned away from the coil 10.

At this point it will be realized that the motor circuit for the motor 10 may be opened in dependence upon the movement of the selector disc 47, as well as upon the operation of the switch section of gauge 37. It has already been explained that energization of coil 42 depends upon the completion of a conductive circuit through the selector disc 47. It has, also, been explained that energization of coil 10 results in circuit-closing movement of switch actuator 80. Since the switch 74, which is embodied in the pressure gauge 37, when opened causes the deenergization of coil 10, thereby to break the motor circuit, it is essential to provide a so-called "locking" circuit for positively preventing the motor circuit from being deenergized when contact finger 14 opens in response to a build-up of the air pressure in reservoir 15.

As will be explained in detail at a later point, the pressure gauge 37 comprises a switch section which includes the metallic pivot post 61, to which are secured pivotally the contactors 60, 81 and 14. When the contactor 14 is in circuit-closing position, then the other two contactors 81 and 60 are similarly in such closing positions. It is to be understood that the opening of these last named switches affects the energization of coil 10 only when the relay coil 42 is in energized state, i. e., during the "active" periods of timer disc 47. Assuming for the sake of illustration that it is desired to trip, or open, the motor circuit when the pressure in reservoir 15 is equal to about 30 mm., and the pressure gauge has been pre-adjusted to open the contactor 81 at 30 mm. pressure, then the pressure gauge is constructed so that the contactor 14 is opened at a pressure of, for example, 2 mm. less than the pre-determined maximum operating pressure. When the pressure responsive element 14' (schematically shown in Fig. 9) opens contactor 14, the coil 10 remains in energized condition, thereby not affecting the operation of motor 10. That opening of contactor 14 does not affect energization of coil 10 will be seen from the fact that the switch 82-83 is in closed position forming a complete circuit through contactor 81.

This by-pass, or shunting circuit, across switch 14 may be traced through the following path: contactor 82, contact 83, lead 84, terminal 85, lead 86, contactor 81, metallic post 61. When the pressure-responsive element opens switch 81 at the maximum pressure of 30 mm. the shunting circuit just described is opened, and this results in deenergization of coil 10. When the coil 10 is deenergized, the switch 23-24, as well as switch 82-83 is opened and the motor circuit thereby broken. Should the pressure in reservoir 15 begin to fall from the maximum value, still assuming that the coil 42 is energized, then the contactor 81 will be the first to swing into closed position but have no effect on the shunting circuit. This follows from the fact that the switch 82-83, which is in the shunting circuit, is still open; and, of course, switch 82-83 remains open as long as coil 10 is in deenergized state. Current will not flow through the circuit including coil 10 until the switch 14 is closed by the pressure-responsive element which continues in its movement from switch 81 to switch 14 as the air pressure in reservoir 15 decreases toward 28 mm. As soon as switch 14 has closed, the circuit including coil 10 is energized; and the element 80 is actuated to close the motor-energizing

switch 23-24 and the "locking" circuit switch 82-83.

Generally speaking, the pressure gauge 37 comprises a casing within which is disposed a disc 90 of insulating material upon which is mounted the post 61, the disc 90 being mechanically coupled to the large gear 91. The gear 91 is driven by pinion 92 geared to the drive gear 93, and the latter being mechanically coupled to the manually adjustable knob 94. It is pointed out that the construction of the pressure gauge mechanism will be described in further detail at a later point, it being sufficient for the present purpose to point out that the knob 94 may be actuated to adjust the angular position of post 61, and its associated contactors 74-81-60, to a predetermined position with respect to the pointer 95. The latter is mounted on a shaft whose rotation is responsive to changes in air pressure in reservoir 15. The element 74' moves with the pointer 20 95 in response to the pressure actuated shaft 172. The index pointer 96 is pre-set, upon actuation of knob 94, to the maximum desired pressure indicated on the gauge dial 97.

In order to provide an emergency, or safety, switch for the pressure control mechanism, the contactor 60 is provided at an angular spacing from contactor 81, say for example 5 mm. of pressure, whereby the relay coil 42 may be automatically deenergized should the switch contactor 81 of gauge 37 open and the motor 10 still remain energized for some unknown reason. The safety switch circuit may be traced through a path which includes: contactor 60, lead 59, terminal 58, lead 57, coil 42, lead 45, contact finger 46, disc 47, finger 48, lead 49, contact 51, contactor 53, lead 55, switch 9 to the source 11, and then through lead 65, lead 64, terminal 63 and lead 62 to metallic post 61. When this safety circuit is open the relay coil 42 is deenergized, and, as a result, the bar 40 will be pulled into position to open pressure release valve 36.

An indicator light network is employed visually to indicate the various functions of the machine. For example, a green light 100 is employed to indicate when there is no air under pressure in the cuff 32 thereby indicating that the pressure release valve 36 is open, and the motor circuit is deenergized. The green light 100 is connected to one side of source 11 through leads 65 and 27; the opposite terminal of the light is connected to the opposite side of source 11 through a path which includes lead 101, switch 19-18 to lead 17, switch 9. As shown in Fig. 9, the green light is energized, because the coil 42 is deenergized, the motor circuit being open and cuff 32 being deflated.

A yellow light 102 is employed to denote the fact that the motor circuit is closed, and cuff 32 is being inflated. During this period, of course, the pressure in reservoir 15 is rising to its maximum value. One terminal of light 102 is connected to source 11, by leads 65 and 27, while the other terminal of the light is connected to the source 11 through a path which includes lead 103, switch 24-23, lead 21, lead 20, switch 19-18, lead 17 and switch 9. It will be seen that with the yellow light energized, the green light 100 is "off", and the motor circuit closed, the cuff 32 being in the process of inflation since the pressure release valve is closed. The red light 104 indicates the fact that the motor circuit is open and the release valve 36 is closed, the pressure in reservoir 15 having reached its maximum value. One terminal of the indicator 104 is con-

- nected to source 11 by leads 65 and 27, whereas the other terminal is connected through switch 241-23, leads 21 and 20, switch 19-18, and lead 17 to source 11.
- 5 There now will be described the general construction of the timing mechanism and its associated electrical circuits, attention being called to the fact that the constructional details of the timer mechanism are described at a later point.
- 10 The timer comprises a metallic disc 47 which is mechanically coupled by a driving shaft 105 to a constant speed motor 106. Although the motor 106 may be designed to operate at any desired revolutions per unit of time, it is pointed out, by way of example, that the motor 106 operates at one revolution per hour, the motor being of any well-known type used in present day alternating current mains-operated clocks. The motor 106 has its terminals electrically connected to the 60 cycle alternating current source 11, and it will be seen that the switch 9 controls the energization of the motor 106, as well as the energization of the remaining circuits. The metal disc 47 is provided with a plurality of insulation segments 107. It will be noted that there are provided two concentric circles of these segments, the outer circle including 15 equidistantly spaced segments of the same shape, and the inner circle comprising 10 segments equidistantly spaced from each other and spaced from the outer circle. It will be observed that the segments 107' of the inner circle are of a configuration different from that of the segments 107.
- A pair of opposed banks of contact fingers is associated with the circles of segments. One of these banks comprises four fingers 46, 103, 109, and 110. These fingers are spaced from each other, and are arranged in parallelism with the terminals thereof secured to an insulating block 111. The opposing ends of these fingers are disposed in wiping, or contact, relation to the segments of the disc 47, as can be better seen in Fig. 9. It has already been explained that the finger 46 is constantly in contact with the metal face of the disc 47, and that the lead 45 connects the finger 46 to the terminal 44 of the relay coil 42. The fingers 109 and 110 are adapted to contact the inner circle 107', whereas the finger 108 contacts the outer circle of segments 107. Each of fingers 108, 109, and 110 is electrically connected to a contact stud in the frequency selector 52. Thus, finger 108 is connected by lead 112 to the stud 51'; the finger 109 is connected by lead 113, to a stud 114. The finger 110 is connected by lead 55 115 to the stud 116.
- The second bank of fingers, in general, duplicates the first bank in that it comprises four fingers 48', 48, 48'' and 117. The terminal ends of these parallel fingers are rigidly secured to insulating block 118, while the wiping ends of fingers 48' and 48 are adapted to be in sliding contact with the outer segments 107. The free ends of finger 48'' and 117 are adapted to be in sliding contact with the inner segments 107'. It will be noted that each of the fingers of this bank is, also, electrically connected to a contact stud of the frequency selector 52, the finger 48' being connected by lead 119 to the contact stud 120. The finger 48 is connected by lead 49 to the stud 51; the finger 48'' is connected by lead 53' to the stud 121, and the finger 117 is connected by the lead 122 to the stud 123. It will be noted that the contact studs of the selector 52 are equidistantly spaced and arranged in a circle, the 75 rotatable contactor 53 being constructed and ar-

ranged for sliding contact with the studs. Dotted lines have been shown to represent blank studs which are not electrically connected to any of the timer fingers. As previously explained the contactor 53 is connected by lead 55 to source 5 11 through switch 9.

In order to explain the operation of the timer mechanism let it be assumed, as shown in Fig. 9, that the contactor 53 of frequency selector 52 has been adjusted to contact studs 51 and 120, 10 these studs being electrically connected to fingers 48 and 48' respectively. In this position of the selector contactor, the relay coil 42 will have an "on-off" cycle of two minutes; that is to say, the coil 42 will be energized for one minute and de- 15 energized for one minute. This cycle is secured by arranging the segments 107 at spacings from each other corresponding to one minute intervals. In other words, the spacings between the segments 107 represent intervals during which 20 the coil 42 is energized for a period of one minute. Each segment 107 occupies an angular distance which corresponds to three minutes of time interval. Hence, in one revolution of motor 106 contact fingers 48 and 48' will slide into and out 25 of contact with each of the segments 107.

Since the finger 48 has a length which exceeds that of 48' by a distance equal to twice the spacing distance between successive segments 107, it will be seen that the coil 42 will only be en- 30 ergized for one minute periods, and deenergized for one minute periods. This follows from the fact that the electrical circuit through the contactor 53 and coil 42 will only be closed when either of fingers 48 or 48' is in contact with a 35 space between successive segments 107. It will be observed that in Fig. 9 the selector switch has been adjusted to studs 51 and 120 so as to select the "on-off" cycle determined by fingers 48 and 48'. In other words, a timer finger is 40 electrically effective when the selector contactor 53 has been adjusted to make contact with a stud corresponding to a particular timer finger.

By way of illustration, the segments 107' are shown as of a different timing pattern. Each 45 segment 107' has an angular distance equal to a five minute interval, and the spacing between segments are equal to a one minute interval. It is to be understood that spacing appearing in the body of each segment 107' represents a one 50 minute time interval. Since the contactor 53, as shown constructed in Fig. 9, can only contact three studs or less, it will be seen that many combinations of "on and off" periods can be secured by proper selection of selector studs. The seg- 55 ments 107 and 107' are not limited to the timing patterns disclosed herein, but they may assume various shapes which are desired for any desired timing conditions. Furthermore, the timer disc 47 may be provided with additional insulation 60 segment circles; and conversely, the timer disc may be simple and utilize only the outer circle of segments 107. Obviously, the number of fingers used for the timer disc will depend in length and number upon the timing cycles desired, and the 65 construction of the frequency selector 52 may be employed to lessen or increase the number of combinations in the timing cycle. Again, the motor 106 can be varied in speed, if it is desired to introduce another range of timing possibilities. 70 The motor 106 need not be an electrically energized motor, but, in general, it can be any constant speed device capable of driving disc 47.

There will now be explained the mechanical construction details, as well as the relative posi- 75

tions, of the elements which are schematically shown in Fig. 9. It has previously been explained that Fig. 1 shows the appearance of the operating panel of the apparatus; the frequency selector device 52 being shown labelled "Frequency," and the numeral 4 denoting the manipulating knob which adjusts the position of contactor 53 of Fig. 9. It will be seen that any desired combination of "on-off" cycles may be selected by rotating the knob, and in Fig. 1 it has been shown that a cycle of one minute "on" and three minutes "off" has been selected. To make this change from the position shown in Fig. 9, it is only necessary to adjust contactor 53 to contact solely with stud 51', thereby selecting finger 108.

The pressure control knob 94 on the operating panel in Fig. 1 is shown arranged to pre-set the position of index 96 of the pressure gauge 37, and it will be observed in Fig. 1 that both this index 20 and the pointer 95 are movable across the face of dial 97. The mechanical details of the pressure gauge 37 are shown in fuller detail in Figs. 7 and 8, and will be described at a later point. Referring now to Figs. 2, 3 and 4, it will be seen 25 that the motor 10, compressor 12 and equalizer 14 are mounted on a chassis pan 130. The equalizer 14, as seen in Fig. 2, is rigidly secured to the pan by brackets 131, the coupling 132 providing the air connection between compressor 12 30 and the equalizer. While the compressor 12 is shown coupled to the motor 10 by a belt drive 12', it is to be clearly understood that any other type of mechanical coupling may be employed such as gears, chain drive or flexible coupling.

Fig. 2 additionally shows the gears 93 and 92 which mechanically couple the knob 94 to the gear 91 of the pressure gauge. Reference is made to Fig. 3 and Fig. 4 which show more particularly this gear relation, as well as the position of 40 the pressure gauge casing on the rear face of the operating panel. Within the interior of the pan 130 are mounted the reservoir 15, the "on-off" switch 9, the fuse 16, frequency selector 52, the timer disc 47 and its associated fingers, motor 106, rubber cushions 13, and the wiring cables denoted generally by the numeral 132'. On the exposed face of the pan 130 are mounted, in addition to the motor, compressor and equalizer, the relays 42' and 70'. It will be understood that 45 the numeral 42' denotes the assembly of elements which includes relay coil 42 and its associated switches. As shown by the dotted rectangle in Fig. 3, these elements are all normally housed within a shield can, and Fig. 2 shows the appearance of the shield can. It will be observed that the relays 70' and 42' are arranged at one side of the pan with the relay 70' to the rear. Fig. 2 further shows the air connection between the reservoir 15 and the equalizer 14, the check valve 30 being disposed in the rubber coupling connection to the air tap 35. The air connection between reservoir 15 and the pressure gauge 37 is shown in Fig. 2, and it will be understood that 50 this connection comprises a rubber coupling 37' between the pressure gauge 37 and the air tap 34.

In order effectively to eliminate vibration and noise due to the operation of the motor and compressor, they are mounted on rubber cushions 13. 55 The cushions are each secured at the ends thereof to the undersurface of pan 130, and in Fig. 3 are shown the bolts 13' which rigidly fix the ends of the cushions to the pan. The motor 10 and compressor 12 are both rigidly secured to a plate 10', 60 shown as a dotted rectangle in Fig. 3, and the

plate is bolted at its four corners to the pair of cushions 13. Fig. 3 shows the bolts 16' which rigidly affix the bedplate 10' to the rubber cushions. In this way there is a so-called "floating power" suspension provided for the motor-compressor unit. It will be observed from Fig. 3 5 that the equalizer 14 is positioned between relay 70' and the motor compressor unit. Further, the synchronous motor 106 is positioned to the rear of a special compartment 130', and within this 10 compartment are housed the timer disc 47 and the contact fingers thereof. As shown in Fig. 3, the contact fingers are affixed to block 118. It will be understood that the second block 111, and its associated contact fingers, will be mounted 15 within the compartment 130'; the compartment is bolted to the pan 130.

In Fig. 4, there is shown the manner of positioning the indicator lights 109, 102 and 104 on the rear face of panel 3. A detail of the indicator 20 light 104 is shown in Fig. 5, and it will be seen that the light 104, or bulb, is secured to the rear face of panel 3 by a bracket 104'. There is provided a conventional socket for the bulb, the electrical leads 140 to the socket being spaced by 25 insulation washers. The bracket end is gripped between the washers; the other end of the bracket 104' is gripped between the rear face of panel 3 and a threaded nut 140'. The latter is threaded to a tube 141 which is affixed to a bore 30 in panel 3 by an outer thread. The glass bezel, or glass lens, 7 is fitted across the outer opening of tube 141 by any well known form of securing device 7'. The lens 7 may be colored red; or the bulb 104 may, if desired, have a red coating and 35 the element 7 be colorless. It will be understood that the remaining indicators 102 and 100 are similarly constructed; in each case the bulbs may be coated with the specific color desired, or the viewing lenses may be colored. 40

A detail view of the timer disc is shown in Fig. 6; and it will be observed that the disc 47 has been sectioned to show the manner in which the outer segments 107 and the inner segments 107' are provided. The disc is preferably made of 45 copper, and is produced with spaced depressed, or shallow, areas corresponding to segments. These shallow areas are filled with shellac, or some other thermoplastic insulation material capable of hardening at room temperature. In 50 this way the spaced circles of segments 107 and 107' are provided. The disc 47 may be electroplated on a patterned mold, such a method of producing a disc with spaced, shallow areas being well known to those skilled in the art. Of course, 55 the copper disc 47 will be of relatively thin plate, and the shallow areas thereof will be given such shapes as is desired. The shellac is poured over the face of disc 47 to fill the shallow depressions thereof; after solidification the excess shellac is scraped, or rubbed, from the disc face by any desired abrasion method. The shellac segments will finally appear as shown in Fig. 9.

The disc 47 is shown rigidly coupled to synchronous motor shaft 105; the disc is secured by 60 rivets 142 to a hub 143. The latter is rigidly affixed to the shaft 105, insulation washers 143 spacing the disc and rivets from shaft 105. In Fig. 3 is shown the disc 47 with its rigid insulation coupling to motor 106. 65

There will now be described the structural details of the pressure gauge 37, special attention being directed to Figs. 7 and 8 showing longitudinal and transverse sections of the gauge. The 70 gauge comprises, in general, a pressure-respon- 75

sive indicator section, and a pressure-actuated motor circuit control section. The gauge comprises a pair of cylindrical casing sections which are secured, as by set screws, to provide a casing 5 ^{37''} having a solid base 150; the latter has a central bore into which is threadedly fitted the air inlet port 151. The forward casing section may be composed of a phenol condensation product, and the rear casing section of metal; or both 10 sections may be of metal. As shown in Fig. 9, the air connection 37' is made from air tap 34 to this port 151. The open end of casing 37'' is closed by the circular window 152 through which is viewed the pressure dial 97. The window 152 15 may be made of glass, Cellophane plate or any other transparent material. The dial 97, bearing pressure indicia as shown in Fig. 1, is spaced from the window 152 to accommodate the pressure actuated pointer 95 and the pre-set index 20 96. The casing 37'' is provided with spaced, peripheral, bored bosses 153 to permit the casing to be secured to panel 3 in the position shown in Figs. 1 and 3.

The dial 97 is rigidly affixed to a pair of spaced 25 metal posts 154, and these posts are rigidly affixed in turn to the rear casing section. For example, the posts 154 may be threaded to the base 150 of the casing. The pointer 95 is actuated by changes in pressure within the aneroid shell, or 30 bellows, 155. This shell is of a conventional and well known construction, and comprises a pair of opposed metallic plates, which are very thin, and each plate being corrugated. The plates are sealed at their periphery, as is well known to those 35 skilled in the art. This expansible diaphragm 155 will swell upon admission of air under pressure. The rear plate 155' of the diaphragm is rigidly affixed to the foundation block 156, and the latter is in turn, secured to the spacer 157. 40 It will be understood that the port 151 has an air connection to the interior of bellows 155, a narrow bore being provided from the port 151 through the various members between the plate 155' and the port.

The forward plate 158 of the aneroid bellows is 45 mechanically coupled to a link connection shaft 159 which has provided on it a pinion 160. The pinion is geared to quadrant gear 161, and the latter is pivoted between pair of supporting plates 50 162 and 163. These support plates are maintained in spaced relation by posts 164. The quadrant 161 is actuated by a pin 165, the pin being rigidly secured to the rod 166. This last named rod is mounted between blocks 164', both 55 of which blocks are secured to the rear face of plate 163. It is to be noted that the plate 163 is broken away in Fig. 7 to show the relation between the quadrant 161, rod 166 and pin 165.

The ends of rod 166 are pivotally secured to 60 blocks 164' by substantially frictionless bearings; and these bearings are shown as conventional conical bearings. The rod 166 is rotated about its bearings by means of a coupling to plate 159, the coupling comprising a yoke member 171 rigidly secured to plate 158, and the yoke being in contact with a pin 170 projecting from the rod 166. As shown in Fig. 7, the pin 170 projects away from the plane of the paper, and is to be understood to 65 be in contact with the forward portion of the yoke 70 171. In this way, when the air pressure expands diaphragm 155, the yoke 171 pushes against pin 170 thereby rotating rod 166. This, in turn, swings pin 165 through an arc, and causes motion of the quadrant 161, about its pivots. The angular motion of the quadrant 161 is converted into 75

rotational motion of pinion shaft 159. The pinion shaft 159 is supported between plates 162 and 163, a spring 171' normally maintaining the shaft in its zero pressure position. The coil of the spring is shown positioned about the shaft adjacent its bearing on plate 163, and the outer end of the spring being secured to post 164. This is shown more clearly in Fig. 10.

The pointer 95 is rigidly secured to the pinion shaft 159 by means of an extension shaft 172, the extension shaft having a hub section 173 which is provided with a bore receiving the tapered end of pinion shaft 159. The tapered end of the pinion shaft is frictionally fitted into the hub section 173 so that the pointer 95, extension shaft 172 and pinion shaft 159 move as a single unit. Hence as the bellows 155 expand, this expansion is translated into a rotary pressure indication of pointer 95; the spring 171' normally biasing the pointer 95 to the zero reading on dial 97. Of course when the chamber 155 is deflated, the spring 171' restores the pointer to its zero position.

It is pointed out that the construction of the pressure gauge up to this point is of a well known form, and is, in general, of a type well known in low air pressure indicating instruments, such as employed in barometers, air speed indicators, etc. The rotational movement of the shaft 172 is utilized to perform an additional function; this function is the control of the motor energizing circuits in response to air pressure variations. In Fig. 9, the pressure gauge has been shown as including three switches comprising contactors 60, 35 81, and 74. In Fig. 7, these contactors are shown as independent pointers, or pins, mounted for rotation about a metallic post 61. The post 61 is riveted to an insulating disc 90. This disc 90 is screwed to a metal collar 90' and the gear 91. The gear 91, collar 90' and disc 90 are securely fitted, as one unit, to a support tube 180. A shoulder on the forward end of the tube bears against the exposed face of dial 97, and a spring washer 181 disposed between the forward face of gear 91 and the rear face of dial 97, positively maintains the gear unit properly centered on support tube 180. The index 96 is rigidly affixed to the shoulder of the support tube 180 so that rotation of gear 91 results in movement in unison of index 96, the support tube 180, washer 181 and the disc 90. 40 45 50

A slot 91' is provided in the periphery of casing 37' in alignment with gear 91, the slot 91' being adapted to receive the intermediate gear 92, shown in Fig. 9, which is driven by rotary adjustment of knob 94. It will, therefore, be seen that adjustment of knob 94 varies the position of index 96 with respect to the indicia on dial 97 so as to indicate the maximum operating air pressure desired. Simultaneously the adjustment of knob 94 pre-sets the position of post 61, and its associated contactors, to a predetermined angular position with respect to the dial index 96.

The contactors are disposed in axial alignment between a shoulder at the free end of post 61 and the disc 90. Each contactor is provided with a hub; and each hub is disposed within the center of a spring coil, as more clearly shown as in Fig. 8. In this last figure, it will be seen that the contactor 60 has its hub secured to one end of spring 70 60', the other end being rigidly secured to a post 61'. The post 61' is rigidly affixed to the disc 90 so as to move therewith, and it will be understood that the spring associated with each contactor has one end thereof rigidly affixed to post 61'. 75

Each coil spring biases its respective contactor into contact with its respective connection post. Thus, the contactor 60 is normally spring biased into electrical contact with post 200; contactor 81 is spring biased into electrical contact with post 201; and contactor 74 is normally biased into electrical contact with post 202. These posts 200, 201, 202 are spaced from each other, and each of them is rigidly affixed to the insulation disc 90. 5 It will be noted that these contact posts are riveted to the insulation disc in the same manner as post 61. Of course, the electrical connections to these contact posts will be readily understood from Fig. 9, which shows the connections between 10 the gauge binding posts and the contact posts associated with each respective contactor pivotally mounted on post 61.

Referring again to Fig. 9, it will be observed 20 that the member 74' has been described as being adjustable in synchronism with pointer 95 in response to increase, or decrease, in air pressure. In Fig. 7 it will be seen that the member 74' physically comprises a trip arm, or vane, one end of 25 which is rigidly secured to the hub section 173 of extension shaft 172; and any well known form of affixing device may be used for this purpose. The free end of the vane is bent at right angles, and is provided with a coating of insulating material 30 74''. It will be noted, furthermore, that the bent section 74'' of the vane has a length such that it is capable of tripping contactors 74, 81 and 60 in succession. Additionally, the section 35 74'' is in alignment with the pointer 95, and such alignment persists throughout rotational movement of shaft 172. As shown in Fig. 7, expansion of diaphragm 155 results in rotation of tripper member 74' away from the plane of the paper until section 74'' contacts contactor 74. Further 40 movement of the vane causes contactor 74 to move in unison therewith, and still further rotation of the vane results in moving contactors 81 and 60 45 out of electrical connection with their respective contact posts.

A special stop post 300 may be provided on disc 45 90 so that when the vane 74' has opened the contactor 60 it cannot be moved beyond stop 300. As explained in connection with Fig. 9, the contactor 81 is designed to open the motor circuit 50 at an air pressure corresponding to the maximum operating air pressure. Therefore, in actual practice the index 96 will be set in alignment with contactor 81 so that the index will actually indicate the pressure at which the motor circuit will 55 open at maximum pressure. Of course, Fig. 9 being schematic, the index 96 has not been shown in alignment with contactor 81, this having been omitted to permit a clear showing of the electrical relations between the contactors and the circuits thereof. As the vane member 74' rotates back to its zero, or normal, position, the contactors 60, 81 and 74 swing back into 60 electrical contact with their respective contact posts. Each contactor has been shown provided with a counterweight 301 to provide symmetry of design and balance. The contactor 74 will be 65 opened when the air pressure increases to a point 2 mm., less than the maximum pressure, whereas the contactor 60 opens when the maximum operating pressure has been exceeded and the motor circuit fails to open.

It will now be appreciated that the pressure gauge is a combined indicating and motor circuit control mechanism. Adjustment of knob 94 pre- 70 sets the motor circuit control switches to a pre-determined angular position with respect to

pointer 95 and vane member 74', the index 96 showing this position as a maximum operating pressure. Increase of air pressure in reservoir 15 is translated, through the agency of diaphragm 155 and the coupling to shaft 172, as a pressure 5 indication shown by pointer 95 and at the same time as a rotational movement of the vane member 74'. Hence, the motor-compressor unit 10-12 is not only regulated by the movement of the timer disc 41, but it is, also, under the control of 10 the pressure responsive mechanism embodied in gauge 37. Additionally, it will be observed that the pressure release valve 36 is only actuated to deflate the cuff 32 when the timer disc 41 de- 15 energizes relay coil 42. Of course, the relay coil 15 42 is also deenergized when the emergency contactor 60 is opened. It is not believed necessary to explain the various electrical conductors and wiring shown in Figs. 3, 4, 7 and 8, because these have been explained in detail in Fig. 9. 20

While I have indicated and described a system for carrying my invention into effect, it will be apparent to one skilled in the art that my invention is by no means limited to the particular organization shown and described, but that many 25 modifications may be made without departing from the scope of my invention, as set forth in the appended claims.

What I claim is:

1. In combination, an air reservoir provided 30 with at least one air coupling for connection to a pneumatic cuff, said reservoir being provided with an air inlet port and a normally open pressure release valve, a relay adapted to close said valve when energized, an energizing circuit connected to said relay for energizing the latter, a motor-compressor unit, said compressor having an air coupling to said inlet port, a control switch connecting said motor to said energizing circuit, said relay being adapted to actuate said control 35 switch upon energization of the relay, a second control switch controlling the energization of said relay, said second control switch including an element constructed and arranged to open and close the circuit through the relay in a predetermined cyclic manner.

2. In an apparatus as defined in claim 1, a third control switch controlling the energization of said motor, and means responsive to an increase in air pressure in the reservoir to a desired 50 pressure for opening the third switch.

3. In an apparatus as defined in claim 1, said element comprising a metallic plate provided with a predetermined pattern of insulation areas, and a constant speed device being coupled to the plate 55 to drive the latter.

4. In a system as defined in claim 1, said last element comprising a constant speed operated-metallic plate provided with a pattern of spaced insulation segments, said second switch comprising 60 a plurality of pairs of contact fingers in contact with said plate, and a frequency selector switch connected to said fingers to select a desired pair.

5. In a system as defined in claim 1, said reservoir being provided with an auxiliary air outlet, and a pressure responsive indicator having an air coupling to said auxiliary outlet.

6. In a venous occlusion apparatus, a cabinet 70 adapted to house a motor-compressor unit, an air reservoir operatively associated with said unit, relays to control the motor circuit and timing mechanism for the motor circuit, an operating panel, means on the panel to pre-set a maximum desired pressure, said means including a device 75

which is automatically responsive to the air pressure within said reservoir, a frequency selector switch, and a plurality of air outlet devices connected to the reservoir.

- 5 7. In combination, in an intermittent venous occlusion apparatus, a cabinet provided with an operating panel, a motor-compressor unit disposed within the cabinet, an air storage chamber having an air coupling to said unit, at least one air outlet means associated with said chamber, means within the cabinet for automatically controlling the operation of said unit in a predetermined cyclic manner, means on the said panel to pre-set a maximum desired air pressure with-
10 15 in said chamber, said last means including a rotatable switch-tripping element having an air coupling to said chamber, and a plurality of control switches in circuit with the motor of said unit, said switches being arranged in succession
15 20 20 in the path of said rotatable element, and a single member for adjusting the position of said control switches with respect to said rotatable element.
25 8. In combination, in an intermittent venous occlusion apparatus, a cabinet provided with an operating panel, a motor-compressor unit disposed within the cabinet, an air storage chamber having an air coupling to said unit, at least one air outlet means associated with said chamber,
30 35 means within the cabinet for automatically controlling the operation of said unit in a predetermined cyclic manner, means on the said panel to pre-set a maximum desired air pressure within said chamber, said last means including a device for automatically controlling the operation of said unit in response to a predetermined increase of the pressure in said chamber, said last named device comprising a control switch connected in the motor energizing circuit, and an air
40 45 pressure-responsive element having an air coupling to said chamber means supporting said element for rotation in a path including said control switch, and means for adjusting the position of said control switch with respect to said element whereby said element is adapted to open said control switch at various pressures in said chamber.

- 50 9. In combination, an air reservoir provided with at least one air coupling for connection to a pneumatic cuff, said reservoir being provided with an air inlet port and a normally open pressure release valve, a relay adapted to close said valve when energized, an energizing circuit connected to said relay for energizing the latter, a
55 motor-compressor unit, said compressor having an air coupling to said inlet port, a second energizing circuit, provided with a control switch,

adapted to be connected to said motor to energize the latter, and said relay having an armature adapted to actuate said control switch upon energization of the relay, and means for controlling the energization of said relay in a predetermined cyclic manner. 5

10. In combination, an air reservoir provided with at least one air coupling for connection to a pneumatic cuff, said reservoir being provided with an air inlet port and a normally open pressure release valve, a relay adapted to close said valve when energized, an energizing circuit connected to said relay for energizing the latter, a motor-compressor unit, said compressor having an air coupling to said inlet port, a second energizing circuit, provided with a control switch, adapted to be connected to said motor to energize the latter, and said relay having an armature adapted to actuate said control switch upon energization of the relay, means for controlling the energization of said relay in a predetermined cyclic manner, a second control switch controlling the energization of the motor, and means responsive to a desired increase of air pressure in the reservoir for actuating said second control switch. 10 15 20 25

11. In combination, an air reservoir provided with at least one air coupling for connection to a pneumatic cuff, said reservoir being provided with an air inlet port and a normally open pressure release valve, a relay adapted to close said valve when energized, an energizing circuit connected to said relay for energizing the latter, a motor-compressor unit, said compressor having an air coupling to said inlet port, a second energizing circuit, provided with a control switch, adapted to be connected to said motor to energize the latter, and said relay having an armature adapted to actuate said control switch upon energization of the relay, and means for controlling the energization of said relay in a predetermined cyclic manner, said last controlling means including a frequency selector mechanism. 25 30 35 40 45

12. In an intermittent venous occlusion apparatus of the type employing a motor-compressor unit and an inflatable cuff air-coupled to the compressor, a timing mechanism to regulate the cuff inflation and deflation periods, a frequency selector device for pre-setting the time duration of said periods, and means, responsive to the air pressure produced by said compressor, for simultaneously maintaining the cuff inflated to a desired pressure during inflation periods and indicating the changes in pressure in the cuff during such inflation periods. 50 55

STANLEY A. KROLL.
